UNITED STATES PATENT OFFICE.

EMIL JUSLIN, OF PHILADELPHIA, PENNSYLVANIA, ASSIGNOR OF ONE-THIRD TO
ERNEST CARLSON, OF PHILADELPHIA, PENNSYLVANIA.

STOPPING APPARATUS FOR RAILWAYS.

1,215,380.

Specification of Letters Patent.

Patented Feb. 13, 1917.

Application filed December 29, 1913. Serial No. 809,158.

To all whom it may concern:

Be it known that I, EMIL JUSLIN, a subject of the Emperor of Russia, and a resident of the city and county of Philadelphia, 5 State of Pennsylvania, have invented a new and useful Stopping Apparatus for Railways, of which the following is a specification.

My invention consists of an improved 10 stopping apparatus for railway trains in which a train will successively during its progress set automatic stopping apparatus for a subsequent train at given points or blocks when passing such blocks, and simultaneously fully release such apparatus at 15 a point previously passed, set and again released, whereby a subsequent train on the same track will automatically be stopped at the block last set until such block is cleared by the preceding train passing out of the 20 block into the next succeeding block.

It further consists of means in such apparatus for releasing from a traveling train a stopping device set by such train in a block 25 next but one to the device being passed, and for partly releasing an apparatus next but one ahead of the block device being passed and which has been set by the last preceding train, whereby said apparatus will be prepared 30 to be released by the first train when the same passes an apparatus in a subsequent block.

It further consists of means for automatically actuating brake-mechanism upon a 35 train when the latter passes onto a blocked track-section.

It further consists of means for automatically setting successive stopping devices in successive blocks of a railway track and 40 partly releasing the stopping devices preceding such device from an engine or car traveling upon the track.

It further consists of such a blocking apparatus in which all of the power for operating 45 the operated apparatus is generated by the operating apparatus.

It further consists of other novel features of construction, all as will be hereinafter fully set forth.

50 The annexed drawings and the following description set forth in detail one mechanical form embodying the invention, such detail construction being but one of various mechanical forms in which the principle 55 of the invention may be used.

In said annexed drawings:—

Figure 1 represents a diagrammatic plan view of a track equipped with my improved system, the relative distances between each apparatus being excessively shortened in 60 their proportions to other parts.

Fig. 2 represents a longitudinal section of the actuating mechanism.

Fig. 3 represents a plan view, partly in horizontal section, of said parts.

Fig. 4 represents a longitudinal section of the pump and actuating mechanism, with the parts in the position with the pump nearly emptied.

Fig. 5 represents a rear view with parts 70 broken and removed of the actuating mechanism.

Fig. 6 represents a perspective detail view of the inner sliding bolt carrying the receiving cam.

Fig. 7 represents a perspective view of 75 an adjusting rod.

Fig. 8 represents a perspective detail view of the sliding casing containing said bolt and cam.

Fig. 9 represents a casing for said bolt.

Fig. 10 represents a detail view of the lock for the sliding casing.

Similar numerals of reference indicate corresponding parts in the figures.

Referring to the drawings, the numerals 1 indicate the rails at the inner sides of which my improved apparatus is arranged. A long box, 2, is supported alongside the rail and has a casing, 3, slideable within it, having a bar, 4, projecting at one end through the open end of said casing and formed with a transverse head, 5, at the end of the bar. A bolt, 6, is longitudinally slideable in said casing and has a bevel, 7, at its end and facing the outer side of the sliding casing. An actuating cam, 8, of substantially quadrant-formed shape is pivoted in a recess, 9, in the inner side of the inner sliding bolt 6, to have vertical swing in said recess and to have a 100 portion project beyond the upper side of the sliding bolt and the upper side of the sliding casing. The segmental edge of said cam has a notch, 10, near its lower end, and one arm of a horizontal movable locking lever, 11, 105 pivoted within a recess, 12, in the sliding bolt, engages such notch when the quadrant cam is tilted upward. A spring-bolt, 13, bears against said arm of the lever and forces the same into the notch when it reg- 110

isters with the same. The other arm of the horizontally movable locking lever is hooked, at 14, and extends out of the recess in which it is fulcrumed, and has play in a groove, 15, in the inner side of the fixed casing or box 2, to engage an adjustable stop, 16, across said groove and preferably near to an opening, 17, in which a forked head, 18, has play to straddle the sliding casing and bolt and to engage notches, 19, in the edges 10 of the sides of the sliding casing without touching the adjustable stop 16. Said forked head is formed upon the inner end of a bolt, 20, slideable in a radially projecting tube, 21, forming a part of the rigid casing and within which is a spring, 22, bearing against a collar 23 upon the bolt and against a tubular nut, 24, secured in the outer end of the tube. A bolt, 25, is secured 20 in the end of the sliding bolt and is slideable in the end-wall, 26, of the movable casing, and said bolt has a spring, 27, coiled around it and bearing against the wall and washers, 28, and a head, 29, upon the bolt. A screw, 30, is journaled in the ends of the stationary casing and at the side of the same, and said screw is threaded through the adjustable stop 16, to adjust the same lengthwise in the casing.

30 Cylinders, 31, are arranged in parallel alinement with the sliding bolt and the sliding and the rigid casings, and pistons, 32, are slideable in said cylinders, and the heads, 33, of said cylinders have pipes, 34 and 35, to which will later be referred. The yoke or head 5 upon the rod of the sliding casing, has two levers, 36, fulcrumed upon its face and near the circumferences, and the outer ends of said levers can engage notches, 37, 35 in rods, 38, extended toward the casings at the open inner ends of the cylinders and from the partitions separating the same, said notches being near the inner ends of said guide-rods. The head 5 is slideable upon the 40 rods 38 by notches, 39, in their upper and lower corners, the yoke being substantially rhombic. Each piston has a piston-rod formed with a conical shoulder, 40, against which the inner end of one of the levers 36, 45 can bear and be pushed outward when passing over it, and said rods have springs, 41, around them which bear against the pistons and the faces of the yoke.

50 A shaft, 42, is journaled transversely to the track and has an upwardly projecting arm 43, the upper end of which has a longitudinal slot, 44, and a rod, 45, is secured to the sliding casing and has a longitudinal slot, 46, which is connected to the rocking arm by a bolt, 48, secured through the two slots. An arm, 49, is secured upon the shaft 55 60 65 42 to be struck by a projection upon the car or locomotive passing over it, or preferably by the following means. A train-pipe, 50, is suitably secured beneath the railway car or

locomotive and has a depending pipe, 51, the lower portion, 52, of which is provided with a cock, 53, which has an arm, 54, which may be tilted when struck by the arm 49, to relieve the pressure in the brake-system of the 70 car and thus apply the brakes on the same, and also cut out steam power on the locomotive.

A shoe, 64, is secured to a locomotive or car to actuate the automatic stop-device, being capable of being raised or lowered at will and in a manner not necessary to illustrate, and a bolt, 65, projects outward from said shoe and has a roller, 66, which is adapted to travel on the adjacent rail of the 75 80 track.

When the device is to be employed, an apparatus like the one described is placed at the end of each section or block of the track, alternately at opposite sides of the track and 85 the locomotives of the several trains traveling on the track are equipped with the shoes and train-pressure reducing apparatus heretofore described.

An apparatus is arranged at each end of 90 each section which may be of whatever length the block-sections are desired to be, say, for instance at a distance of a mile, one from the other.

When now the locomotive arrives at the 95 block at the following section and said section is blocked, the lowered shoe engages the straight edge of the cam at said place and first partly moves the cam which is held against rotation by the lever engaging the 100 notch in the segmental edge of the cam.

In describing the operation of the device, it will be assumed that the blocking devices are arranged at one rail of the track and at suitable distances apart according to the 105 desired lengths of the block-sections, one device being provided at the end of each block. With a double track, two series of devices are employed, one for each track.

At the beginning of the trip of a train 110 over a track provided with my system, all of the devices are supposed to be in the position seen in Figs. 2 and 3, with the stopping levers tilted backward and the several devices released and ready to be set.

115 As the shoe upon the passing locomotive or car strikes the straight edge of the cam and moves it and the sliding bolt forward, the beveled end of said bolt engages the end of the transverse latch and pushes the same 120 outward, thereby releasing it from the sliding casing which will subsequently slide forward with the cam and bolt. When the sliding bolt moves forward, the outer end of the relieving lever 11 engages the stationary 125 stop 16 and said lever is tilted to disengage from the notch in the cam, so that, as the shoe moves forward and has pushed the bolt and casing forward, such cam will be released and the shoe in its continued force 130

and movement will tilt the cam downward. As the sliding casing moves, the cross-head upon the bar compresses the springs upon the piston-rods which move the pistons in the cylinders and force the liquid in the same, respectively, to a similar apparatus two blocks ahead and two blocks behind the actuated apparatus. As soon as the latch-levers upon the cross-head arrive at the notches in the guide-rods and the springs have forced the pistons to the ends of the cylinders to withdraw the beveled ends of the piston-rods from the lever-arms, said latch-levers can rock and have their outer ends engage the notches in the guide-rods and hold the cross-head, bar, sliding casing and bolt in position compressing the springs actuating the pistons. It will be understood that the parts are so arranged and proportioned that their operation is such that the pistons 32 are moved sufficiently to permit levers 36 to engage with the notches 37 at a suitable time with respect to the disengagement of the cam 8 by the shoe 64, it being understood that the movement of the pistons 32 will force the liquid from the cylinders 31 through the pipes 34 and 35 respectively. The forwardly moved sliding casing draws the arm 49 upward, so that it can engage the arm 54 upon the brake-mechanism of a following train and actuate the brakes to automatically stop the same, if the preceding train should not have left its second preceding block. The liquid forced rearward from the apparatus which has just been actuated by the train above described as passing over it acts upon one piston in the apparatus in the second block to the rear and forces the same rearward, causing the bevel upon the piston-rod to engage and release one latch-lever from its notch and compressing the spring against the cross-head which is still held by one latch. The liquid which is forced forward from the cylinder of the apparatus described above as operated by the passing train, passes to the apparatus in the second block forward and into one of the cylinders there. If another train which had actuated this apparatus has passed two blocks forward from the same, such train has actuated the other piston and forced it backward, in which case the now actuated piston moves back and the cross-head and sliding casing and bolt move back, giving a clear track and placing the apparatus in condition to be again set. As the cam 8 moves back with the other parts its lower edge rides upon the wall of a slot in the bottom of the box 2 and so is elevated from its position seen in Fig. 4 to that seen in Fig. 2. If the second piston has not been released, the movement of the last-actuated piston will not release the sliding parts and the apparatus will stay blocked until released by the second preceding train.

It will thus be seen that a train passing over one apparatus will partly release an apparatus two blocks ahead and partly release an apparatus two blocks to the rear to be fully released when the succeeding train is within two blocks from the same. A train entering a blocked track will be automatically stopped. As it takes one action by a preceding train and one action of a following train to release the block, the certainty of operation of the apparatus will be assured. as each operation of one apparatus only partly operates the connected apparatus.

Instead of a fluid, such as oil, being employed as the connecting means between the transmitting device the latter may be actuated by an electric circuit without departing from the spirit of my invention.

Other modes of applying the principle of my invention may be employed for the mode herein explained. Change may therefore be made as regards the mechanism thus disclosed, provided the principles of construction set forth, respectively in the following claims are employed.

Having thus described my invention, what I claim as new and desire to secure by Letters Patent, is:—

1. In an apparatus of the character stated, a series of pairs of cylinders, a piston for each cylinder, means actuated by a passing locomotive or car for moving forwardly both pistons of a pair of cylinders, independent means for locking each piston in its forward position, means carried by each piston for releasing its locking means, and separate means for returning said pistons to normal position and to release their locking means, one means operating from one of a distant pair of cylinders in advance of the locked piston and the other from one of a distant pair of cylinders in the rear of the other locked piston.

2. In an apparatus of the character stated, a series of pairs of cylinders, a piston for each cylinder, means actuated by a passing train for moving forwardly both pistons of a pair, means for locking said pistons in their forward position, means carried by each piston for releasing its respective locking means, a pipe connected with one cylinder of one pair and with one cylinder of a distant pair in advance thereof, a pipe connecting the other cylinder of the pair with one cylinder of a distant pair in the rear thereof, and fluid means actuated by the distant pistons to return the pistons to release the locking means and to return the parts to unlocking position.

3. In apparatus of the character stated, a cylinder having an outlet at one end, a piston in said cylinder and having a rod provided with a beveled shoulder, a guide rod formed with a notch, a bar having means for reciprocating it and formed with

1
a yoke, a lever fulcrumed on the yoke having one end adapted to engage the notch of the guide-rod and the other end to engage the shoulder upon the piston rod, and a 5 spring upon the piston-rod and bearing against the piston and the yoke.

4. In apparatus of the character stated, a cylinder having an outlet at one end, a piston in said cylinder and having a piston rod, 10 a guide-rod having a notch, a yoke movable upon said piston rod and guide-rod, means for sliding said yoke, a spring between said piston and yoke, and a lever fulcrumed on the yoke having one end adapted to engage 15 the notch in the guide-rod and its other end constructed to be engaged by the piston-rod to be actuated by the same to disengage its other end from the notch in the guide-rod.

5. In apparatus of the character stated, a 20 casing stationarily supported near the rail of a track, a casing sliding in said stationary casing and having a bar projecting from one end, a bolt sliding in said sliding casing, a substantially segmental cam pivoted in the 25 sliding bolt and extending and longitudinally projecting in the walls of said bolt, sliding casing and stationary casing and formed with a notch in its curved edge, a lever pivoted in a recess in the slidable bolt 30 and having a hooked end capable of being engaged in the notch of the cam and a projecting opposite end, a stop carried by the stationary casing with which the end of the lever engages, a catch in the stationary casing 35 and adapted to engage a stop in the sliding casing, a bolt projecting from the forward end of the sliding bolt, a wall in the forward end of the sliding casing and having said bolt slidable in it, and a spring 40 secured to the forward end of said bolt and against the wall.

6. In apparatus of the character stated, a reciprocable transmitting device, a slidable member having a yoke, a guide-rod for such yoke and provided with a stop, a locking 45 lever upon the yoke and adapted to engage said stop, a yielding expansion element bearing against said yoke and reciprocable transmitting device, and means for detaching the locking lever from the stop of the guide- 50 rod.

7. In apparatus of the character stated, a cylinder formed with a limited outlet, a piston within said cylinder, a rod for said piston and formed with a beveled shoulder, a 55 guide provided with a notch, a bar having means for longitudinally moving it and having a yoke movable upon the guide rod and the piston rod, and a lever pivoted upon said yoke and having one end capable of engaging 60 the notch in the guide-rod and the other end capable of moving over the beveled shoulder of the piston-rod.

8. In apparatus of the character stated, a 65 casing adapted to be supported alongside a rail, a casing slidable in said casing and having a forwardly extending bar, liquid actuating means connected to be actuated by said bar, a bolt slidable in said second casing, an eccentric cam pivoted within the slidable 70 bolt to project through the latter and the casings and formed with a notch in its segmental edge, a lever pivoted in the sliding bolt and having one end adapted to engage 75 the notch in the cam, and a stop within said stationary casing and in the path of the outer end of the lever to rock the same and relieve the notch in the cam.

EMIL JUSLIN.
